UNITED STATES PATENT OFFICE.

NILS DAVID LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,247,422.

Specification of Letters Patent. Patented Nov. 20, 1917.

Application filed October 19, 1912. Serial No. 726,795.

To all whom it may concern:

Be it known that I, NILS D. LEVIN, a citizen of the United States, residing at Columbus, in the county of Franklin and State of Ohio, have invented certain new and useful Improvements in Mining-Machines, of which the following is a specification, reference being had therein to the accompanying drawings.

10 This invention relates especially to continuously cutting mining machines of the type especially adapted for use in mines which are worked according to the "room and pillar" system, and to trucks for use in combination with such machines for transporting them. As to certain features, however, my invention is not so limited, and may be applied to machines of other types.

15 The principal object of the invention is to provide an improved arrangement of gearing and power transmitting mechanism for driving the cutters, for driving and controlling the ropes or cables by means of which the cutter mechanism or the machine 20 as a whole is moved and guided, and for driving the truck upon which the machine may be placed for transportation. Another object is to provide improved means whereby the machine can be reversed for operation in either direction. Another object is to provide improved means whereby power 25 can be applied to the rope which is normally used for retarding the outlet end of the machine. Another object is to provide 30 means whereby the feed cable may be attached at any one of several elevations to change the line of pull. Still other objects will be apparent from the following specification and claims.

35 40 In the accompanying drawings I have shown one embodiment of my invention, but it will be understood that many modifications and changes may be made without departing from the spirit of the invention as set forth in the claims which are hereto appended.

In the drawings,

Figure 1 is a plan view of a mining machine embodying my invention.

45 Fig. 2 is a side elevation.

Fig. 3 is a longitudinal section of a part of the machine taken along the line 3-3 of Fig. 1.

50 Fig. 4 is a section taken along the line 4-4 of Fig. 1.

Fig. 5 is a detail view of the anchor or jack for the feed rope.

Fig. 6 is a plan view of a truck adapted to support the mining machine and to be driven by it.

Fig. 7 is a side elevation showing the mining machine on the truck.

Fig. 8 is a diagrammatic view showing the machine making a transverse cut across the face of a room.

Fig. 9 is a diagrammatic view showing the machine making a transverse cut across the face of a room in the direction opposite to that indicated in Fig. 8.

Fig. 10 is a diagrammatic view showing the machine making a sumping cut.

Fig. 11 is a diagrammatic view showing the machine being moved across a room by means of the rear controlling rope.

Fig. 12 is a diagrammatic view showing a modified arrangement of the feed rope. This view is otherwise similar to Fig. 8.

Referring to the drawings, A represents as a whole the bed frame of the mining machine. This bed frame, in the embodiment shown, comprises several parts. One of these parts is the main frame casting 1, which is secured to and mounted upon a horizontal platform or shoe 2 which is adapted to rest and slide upon the floor of a mine. This shoe constitutes another part of the bed frame, and the motor frame which will be hereinafter referred to constitutes a third part.

Projecting from the main frame 1 is the cutter arm 3 which may be of any of a variety of constructions. As shown in the drawings this cutter arm has a top plate 4 which is formed integrally with the casting 1 and is provided with a central slot 5. Beneath the top plate 4, and similar to it in size and shape, is a bottom plate 6. Between the top and bottom plates there is a spacer block 7 of smaller outline than the plates. The top and bottom plates and the spacer block are held together by suitable bolts or rivets as shown. It will be noted that the top and bottom plates project inward beyond the edges of the spacer block at the center thus forming a slot having in its edges grooves in which a block 8 can slide. The purpose of the block 8 will be made clear hereinafter. At their outer edges the top and bottom plates extend outward beyond the spacer block thus forming a

groove in which the cutter chain 9 is guided. The chain is held in place against outward movement by guide strips 10, 10. At its outer end the cutter chain passes over a 5 sprocket wheel 11.

12 is an electric motor preferably arranged with its armature shaft in vertical position. The frame or casing of the motor is secured at the forward side to the main 10 frame casting 1 and at its lower side to the shoe or platform 2. In this way, as stated above, the casting 1, the motor frame 12 and the shoe 2 form one rigid bed frame structure. Mounted upon the frame of the motor 15 12 is a starting and reversing box 12^a which may be of any usual or preferred construction.

At the upper end of the armature shaft 20 of the motor 12 is a pinion 14 which meshes with an idler gear 15 journaled upon a suitable pin or stud secured to the motor frame. The gear 15 meshes with a large drive gear 16 which is keyed to a vertical drive shaft 17 in a manner to permit the shaft to move 25 vertically. A casing 16^a incloses the gears. The shaft 17 is provided with a shoulder at 18 which engages the hub 19 and limits upward movement of the shaft with respect to the gear wheel.

30 Downward movement of the shaft is permitted under the control of the nut 20 which is threaded on the upper end of the shaft. The nut 20 is held in vertically fixed relationship to the gear wheel by means of the 35 ring 21. The space beneath the ring 21 and surrounding the nut may be used as a reservoir for oil for lubricating the shaft bearings.

22 is a drive element for the drums which 40 will be described below. Preferably this drive element is a rotatable sleeve having a central aperture through which the shaft 17 extends. The hub 19 of the gear wheel 16 is journaled in the central aperture by 45 means of the bearing bushing 23, and the lower end of the shaft is journaled in this aperture by means of the bearing bushing 24. Formed on the sleeve 22 at the upper end thereof is a horizontal flange or disk 25. 50 At the outer edge of this disk 25 there is provided a spur gear 27 which is preferably formed as a separate ring secured to the disk.

Positioned below the disk 25 and secured to the main frame casting 1 is a supporting 55 plate or bracket 28. This plate 28 is provided with a central aperture in which by means of a bearing bushing 29 there is journaled a hub 30 which is connected by a key 30^a to the sleeve 22. By means of this bearing 60 at 29 the upper end of the shaft and the associated parts are supported.

Secured to the plate 28 and positioned directly beneath the gear ring 27 is a similar gear ring 31. The rings 27 and 31 are 65 of the same size but are provided with dif-

ferent numbers of teeth. For example, it may be considered that the ring 27 has ninety teeth and the ring 31 ninety-one teeth. 32 is a bearing pin secured at its upper end to the web of the gear 16 and supported at its lower end by means of a stirrup 33 also secured to the web of the gear. Rotatably mounted upon the pin 32 is a pinion 34 of sufficient width to engage the teeth on the ring 27 and also those on the ring 31. It will be observed that on account of the difference in the numbers of teeth on the gears 27 and 31 the movable gear 27 will, for every revolution of the gear wheel 16, be moved with respect to the fixed gear 31 through a distance equal to that represented by the extra teeth on the fixed gear. If the gears are provided with ninety and ninety-one teeth, respectively, the gear 27 will be moved through the distance represented by one tooth or one-ninetieth of a revolution for each complete revolution of the gear 16, and will be moved in the opposite direction.

As has been stated, the sleeve 22 has secured to it at its upper end a hub 30. Keyed to the sleeve 22 at its lower end is a hub 35. A collar 36 threaded on the sleeve engages the lower side of the hub 35 and the plate 28 engages the upper side of the hub 30. 90 The two hubs are in this way held against being moved away from each other. The hub 35 is journaled in a bearing aperture of the bottom plate of the main casting 1 by means of a sleeve 37. By means of this bearing 95 at 37 the lower ends of the sleeve 22 and of the shaft 17 are supported.

Formed integrally with the upper hub 30 is an outward projecting circular flange 38 which is provided at its outer edge with a 105 downward projecting annular collar 39. Journaled on this collar 39 by means of a bearing bushing 40 is the hub 41 of a winding drum 42. Connecting the upper edges of the hub 41 and the drum 42 is a web 45. 110 Extending from the lower edge of the hub 41 is an inward projecting plate or web 46, the inner edge of which rests upon a ball bearing 47. This ball bearing is supported upon the hub 48 of a hand wheel 49. This hub 48 has threaded engagement with the sleeve 22. In the recess formed between the flange 38 and the web 46 are mounted the disks of a friction clutch 50. These disks are connected alternately with the web 46 120 and the flange 39 in the manner which is well known. It will be clear that by means of the hand wheel 49 the hub 48 can be turned and raised or lowered because of its threaded engagement with the sleeve 22. As 125 the hub 48 is raised the web 46 and the drum 42 are raised and the friction disks of the clutch 50 are forced into engagement with each other. When the hub 48 is lowered the pressure between the disks of the clutch is 130

relieved. In this way the drum 42 can be connected with or disconnected from the flange 39, the hub 30, and the sleeve 22.

For resisting the rotation of the drum 42 I provide a brake band 51 which is adapted to engage the outer surface of the hub 41. The ends of this brake band 51 are secured to oppositely threaded nuts 52, 52, which engage a similarly threaded shaft 53. This shaft is mounted in suitable bearings on the main frame casting 1. By means of hand wheels 54, 54, the shaft 53 can be rotated and the nuts 52, 52 can be moved toward or away from each other to tighten or loosen the brake band 51.

55 is a second drum of considerably less diameter than the drum 42. This drum 55 is journaled on the sleeve 22 by means of the bearing bushing 56. The drum 55 is positioned directly beneath the hub 48 and a ball bearing 57 is interposed between the hub and the drum. Between the drum 55 and the hub 35 before referred to there are located the disks of a friction clutch 58. These disks are alternately connected with the drum and with the hub in the well known manner. When the hub 48 is turned in one direction by means of the hand wheel 49, the disks of the clutch can be forced into engagement with each other, and when the hand wheel is turned in the other direction, the pressure between the disks can be relieved. In this way the drum 55 can be connected to or disconnected from the hub 35 and the sleeve 22. It will be noted that the same hand wheel 49 and the same central hub 48 controls the two clutches 50 and 58. When the hand wheel is turned in one direction the clutch 50 is engaged and the clutch 58 is released. When the hand wheel is turned in the other direction the clutch 58 is engaged and the clutch 50 is released. The two clutches cannot both be engaged at the same time.

45 Journalized on the shaft 17 at the lower end thereof is a sprocket wheel 59 over which the cutter chain 10 passes. This sprocket wheel 59 is provided at its lower edge with clutch teeth 60. The lower end of the shaft 17 is 50 provided with a clutch element 61 having radially extending teeth adapted to lie between and engage the teeth 60 when the shaft 17 is in its uppermost position. The teeth 61 can be disengaged from the teeth 60 by turning the nut 20 by means of a suitable wrench and thus lowering the shaft 17. By lowering the shaft farther the clutch element 61 can, when the machine is on a suitable truck, be brought into engagement with 60 a clutch element on the truck. A projection 62 on the lower cutter arm plate 6 supports the sprocket wheel 59 when the shaft is lowered.

63 is the feed rope connected to the drum 55 to be wound thereon. If the machine is to

be fed toward the left, the rope is wound in the direction indicated in Fig. 1 and is passed off from the inner side of the drum toward the left. The end of the rope can, if desired, be secured to a jack or anchor near the left rib of the room in which the machine is to be operated. However, I prefer to pass the feed cable about a suitable pulley at the left rib and to fasten the end of the cable to the frame of the mining machine. In order that the end of the cable may be easily fastened to the machine, I secure to it a T-shaped button 64 which is adapted to be passed into a similarly shaped vertical slot 65 at the side of the main part of the casting 1 near its inner end. Two of these slots 65 are provided, one on each side, in order that the machine may be fed in either direction in a manner to be described. Adjacent each slot and extending into it are a number of holes 65^a each adapted to receive a pin 65^b. By means of one or more of these pins 65^b the button 64 and the end of the cable, may be secured at any desired elevation. The advantage of this construction 90 will be made apparent hereinafter.

In Fig. 5 I have shown one form of pulley mounting which may be advantageously used at the right rib. This comprises a toothed base plate 66 carrying a cylindrical 95 boss 67 upon which the pulley 68 is journaled. An annular lip 69 on the boss holds the pulley against displacement. The boss 67 is provided with a cup or recess 70 in which can be placed the lower end of a jack 100 71. By means of this jack the whole device can be securely clamped against the mine floor and held against displacement.

72 is a retarding cable connected to the drum 42 to be wound thereon. Mounted 105 upon transverse horizontal axes at the rear end of the machine are idler sheaves 73, 73, positioned with their upper edges in horizontal alignment with the drum 42. 74, 74 are other idler sheaves mounted for rotation about horizontal longitudinal axes. Each of the sheaves 74, 74 is positioned to receive a cable from the corresponding sheave 73 and to guide it across the rear of the machine. For feeding toward the left 115 the rope 72 is passed from the drum 42 over the left hand sheave 73 and under the sheaves 74, 74. The end of the cable is suitably secured by means of an anchor or jack at the right hand rib.

When the machine is to be used in the usual manner for cutting from right to left, as indicated in Fig. 8, the feed and retarding ropes are arranged in the manner described and the motor 12 is started. From the motor 125 power is transmitted through the gears 14, 15 and 16 through the shaft 17 to the cutter chain drive sprocket 59. By means of the gears 32, 31 and 27 the sleeve 22 is rotated slowly in the opposite direction from the 130

shaft 17. The operator by means of the hand wheel 49 causes the engagement of the clutch 58 and thus connects the drum 55 with the sleeve 22. The drum 55 winds the feed rope 63 and the machine is thus drawn toward the left, the cutters on the chain 10 being drawn into the coal. The rear end of the machine is retarded by means of the rope 72, rapid unwinding of this rope 42 being prevented by means of the brake 51. This retarding action can be readily controlled by means of one or the other of the hand wheels 54, 54. By regulating the resistance of the brake 51, the machine can be 15 "angled", *i. e.*, the outer end of the machine can be permitted to advance beyond the inner end, or the outer end can be held back behind the inner end. In case it is desired for any reason to more quickly angle the 20 machine toward the rear, this can be done by releasing the brake 51 and turning the hand wheel 49 to disengage the clutch 48 and engage the clutch 50. With the clutch 50 engaged, power will be transmitted to 25 wind the rope 72 and thus positively pull the rear end of the machine backward toward the right rib.

It will be noted that the entire machine is perfectly symmetrical with respect to a central longitudinal plane and that the machine is therefore adapted to be operated in either direction. To adjust the machine for operation from left to right, as indicated in Fig. 9, it is simply necessary to reverse the 30 cutters of the cutter chain and to unwind the ropes from the drums and rewind them in the opposite direction. As each drum can be readily controlled by means of its friction clutch, the unwinding and rewinding can be 35 done by means of power. After unwinding and rewinding, the button 64 on the feed rope 63 is placed in the right hand slot 65 and the retarding rope 72 is passed over the right hand sheave 73.

45 The adjustable attachment of the feed rope makes it possible to vary the line of draft on the machine in accordance with the conditions of operation. For instance, if it is found that there is a tendency for the forward edge of the shoe 2 to bear too hard against the floor and to dig in and catch, the tendency can be overcome by lowering the point of attachment. If, on the other hand, the conditions of cutting are such that 50 there is a tendency for the forward edge of the cutter mechanism to work upward, the tendency can be overcome by raising the point of attachment of the feed rope. By 55 carefully watching the operation of the machine the operator can adjust the feed rope to the most advantageous position.

60 While I prefer and have described an arrangement in which the feed rope is doubled back on itself and connected with the machine frame, it will be understood that if 65

desired the end of the rope may be connected directly with a jack or other anchor as indicated in Fig. 12.

In Fig. 10 I have shown diagrammatically the arrangement of parts for making the 70 sumping cut. After the machine has been placed in position the block 8 is moved to the inner end of the cutter arm and a jack 75 is passed through its central aperture to secure it in position. This jack, it will be 75 understood, is adapted to engage the roof or coal face at its upper end and the floor at its lower end. This block 8 serves as a guide for the cutter arm as it is moved inward. The feed rope 63 is passed forward 80 over a suitable idler pulley 76 mounted on the main frame casting 1, and the end of the cable is secured to the jack 75. By winding the feed rope the machine can be drawn directly inward until the sumping cut is 85 completed. As the line of pull is central, it will usually be found that no guide for the outer end of the machine is necessary.

For handling the machine and moving it from point to point about a mine room, use 90 can be made of the rope 72. In order that the rope 72 may be passed out from the rear end of the machine in any direction, there are provided idler sheaves 77, 77, mounted for rotation about vertical axes. The rope 95 72 can be passed between these two sheaves and its end can be connected at any desired point. The operator, by engaging the clutch 50, can cause the rope 72 to be wound, and, in this way, the machine can be hauled in 100 any direction. As the drum 42 is considerably larger than the drum 55, the rate of movement of the machine under the control of the rope 72 is considerably greater than when it is being fed forward by means of 105 the rope 63. In Fig. 11 I have shown the machine being hauled toward the right rib after making a cut from right to left.

In order that my improved machine may be readily transported from place to place 110 about a mine, I preferably provide in combination with it a truck such as shown in Figs. 6 and 7. As to the details of this truck there may be variation but the construction which I deem most advantageous is shown in 115 the drawings. This construction is similar to that shown in my co-pending application for mining machines and trucks, Serial No. 557,432, filed April 25, 1910.

The frame of the truck comprises the side 120 rails 78, 78 and cross bars 79, 79, 80 and 81, 81. To the side rails are secured bearing boxes 82, 82 for the axles 83, and 84 to which are secured the track wheels 85, 85, and 86, 86. Chains 86^a, 86^a are provided for 125 connecting the forward wheels with the rear axles. The wheels 85, 85 are not keyed directly to the forward axle 83, but are rotatably mounted upon short shafts or pins 87, 87, which are secured at their inner 130

ends to the crank arms 88, 88. These crank arms are keyed to the ends of the axle 83. This construction provides, in effect, an axle bent at its two ends and the wheels 85, 85 are thus mounted eccentrically with respect to the central part of the axle.

It will be observed that this cranked axle construction makes it possible for the forward end of the truck to be raised and lowered by rotating the axle. When the forward end of the truck is in its lower position the mining machine can be readily moved onto or off from it, and when the forward end of the truck is in its upper position the truck is adapted to be moved along the track. In moving the machine onto the truck the cable 72 is passed to the rear between the sheaves 77, 77, and is secured at a suitable point to the rear end of the truck. The operator by engaging the clutch 50 can cause the cable to be wound and the machine to be moved bodily along the truck. Secured to the crank arms 88, 88 are upstanding horns 89, 89 in position to be engaged by pins or rollers 90, 90 on the frame of the mining machine. When these pins 90, 90 are forced into engagement with the horns 89, 89 by the continued movement of the mining machine, the axle 83 is rotated and the truck is raised to horizontal position.

When the mining machine is in proper position upon the truck the clutch element 61 at the lower end of the main power shaft 35 17 is in mating position over a clutch element 91, which is mounted on the truck frame for rotation about a vertical axis. This clutch element 91 is connected with a drive sprocket wheel 92, there being preferably interposed between the clutch element and the sprocket wheel an intermediate drive plate 93 having grooves 93^a and 93^b, disposed at right angles to each other and formed to receive tongues carried by the clutch element 91 and the sprocket wheel 92, respectively. The plate 93 carries at its center a block 93^c which projects across the grooves 93^a and 93^b and serves to keep the clutch element, drive plate and sprocket wheel part in operative relation to each other. This construction permits the clutch element and the sprocket wheel to rotate about axes which are somewhat out of alinement. By lowering the shaft 17 55 sufficiently by means of the nut 20 the clutch element 61 can be brought into engagement with the clutch element 91 and power thus be transmitted from the mining machine motor to the truck. At the rear end of the truck a vertical shaft 94 is provided. This shaft carries a sprocket wheel in horizontal alinement with the sprocket wheel 92 and over these two sprocket wheels there passes a drive chain 95. Secured to the shaft 94 65 is a bevel gear 96 which meshes with two

other bevel gears 97 and 98 loosely mounted on a transverse shaft 99. By means of suitable clutches controlled by the hand wheel 100 either of the gears 97 or 98 can be operatively connected with the shaft. At 70 one end of the shaft 99 is a sprocket wheel 101 which is in longitudinal alinement with a similar sprocket wheel 102 on the axle 84. A chain 103 passes over these two sprocket wheels and serves to transmit 75 power from the shaft 99 to the axles. It will be clear that by means of the devices which have been described, power can be transmitted from the mining machine motor to the vertical shaft 94. By means of 80 the bevel gears and the clutches power can be transmitted from the shaft 94 to drive the shaft 99 in either direction, and from the shaft 99 power can be transmitted to drive the truck axles. Therefore by means 85 of the hand wheel 100 an operator can cause the truck to be driven in either direction as desired.

Preferably I provide at the rear of the truck a cable reel 104 for winding and un-winding an electric cable 105. This reel is driven by means of a rope belt 106, which passes over a sheave 107 on the power shaft 99. It will be clear that the direction of rotation of the reel is reversed whenever 95 the direction of movement of the truck is reversed. Current is transmitted from the cable and the reel to the mining machine motor by means of an intermediate conductor cable 108. I do not herein claim the reel 100 in combination with the truck nor as an independent mechanism as these subjects-matter are presented in my co-pending applications for mining machines and trucks, Serial No. 579,798, filed August 31st, 1910, 105 and for cable winding mechanisms, Serial No. 664,037, filed December 5th, 1911; nor do I claim herein the truck in combination with the mining machine broadly as that constitutes the subject-matter of my pending application for mining machines and trucks, Serial No. 557,432, filed April 25, 110 1910.

What I claim is:—

1. In a mining machine, the combination 115 of a bed frame, a cutter chain, a support for the cutter chain mounted on the bed frame and serving to guide the chain in a horizontal path, a sprocket wheel for driving the cutter chain, a clutch element on 120 the sprocket wheel, a vertical drive shaft in axial alinement with the sprocket wheel and extending upward to the top of the machine, a motor connected with the shaft, a clutch element on the lower end of the shaft, and 125 a device at the upper end of the shaft for moving it vertically to bring the clutch element thereon into or out of engagement with the clutch element on the sprocket wheel.

2. In a mining machine, the combination 130

of a bed frame, a cutter chain, a support for the cutter chain mounted on the bed frame and serving to guide the chain in a horizontal path, a sprocket wheel for driving the cutter chain, a clutch element on the sprocket wheel, a vertical drive shaft in axial alinement with the sprocket wheel and extending upward to the top of the machine, a motor connected with the shaft, a clutch element on the lower end of the shaft, a device at the upper end of the shaft for moving it vertically to bring the clutch element thereon into or out of engagement with the clutch element on the sprocket wheel, a rotatable drum mounted concentrically with the drive shaft and fixed against relative axial movement, mechanism for transmitting the power of the motor to rotate the drum, and a rope engaging the drum and adapted to have its end secured at a fixed point to cause the bodily movement of the cutter chain and support as the drum is rotated.

3. In a mining machine, the combination of a bed frame, a cutter chain, a support for the cutter chain mounted on the bed frame and serving to guide the chain in a horizontal path, a sprocket wheel for driving the cutter chain, a vertical drive shaft connected with the sprocket wheel in alinement therewith, a motor connected with the drive shaft, a rotatable drum mounted concentrically with the drive shaft, mechanism for transmitting the power of the motor to rotate the drum, and a rope engaging the drum and adapted to have its end secured at a fixed point to cause the bodily movement of the cutter chain and support as the drum is rotated. . . .

4. In a mining machine, the combination of a bed frame, a cutter chain, a support for the cutter chain mounted on the bed frame and serving to guide the chain in a horizontal path, a sprocket wheel for driving the cutter chain, a vertical drive shaft connected with the sprocket wheel in alinement therewith, a motor connected with the drive shaft, two rotatable drums mounted concentrically with the drive shaft, mechanism for transmitting the power of the motor to rotate one of the drums, a rope engaging the said drum and adapted to have its end secured to a fixed point to cause the movement of the cutter chain and support as the drum is rotated, a rope engaging the other drum and adapted to have its end secured at a fixed point, and means connected with the said other drum for tensioning the said rope.

5. In a mining machine, the combination of a bed frame, a cutter chain, a support for the cutter chain mounted on the bed frame and serving to guide the chain in a horizontal path, a sprocket wheel for driving the cutter chain, a motor connected with the sprocket wheel, a vertical drive element

connected with the motor and concentric with the sprocket wheel, a rotatable drum mounted concentrically with the drive element, a hand-wheel adjacent the drum and having threaded engagement with the drive element, a clutch for connecting the drum with the drive element, the clutch being controlled by the movement of the hand-wheel with respect to the drive element, and a rope engaging the drum and adapted to have its end secured at a fixed point to cause the bodily movement of the cutter chain and support as the drum is rotated.

6. In a mining machine, the combination of a bed frame, a cutter chain, a support for the cutter chain mounted on the bed frame and serving to guide the chain in a horizontal path, a sprocket wheel for driving the cutter chain, a motor connected with the sprocket wheel, a drive element connected with the motor, two rotatable drums mounted concentrically with the drive element, a hand-wheel between the two drums having threaded engagement with the driving element, two clutches connected with the hand wheel to be controlled by its rotation with respect to the drive element, one clutch serving to connect one drum with the drive element and the other clutch serving to connect the other drum with the drive element, and two ropes respectively engaging the drums and adapted to have their ends secured at fixed points whereby force can be applied to the cutter chain support through either rope when the corresponding drum is rotated.

7. In a mining machine, the combination of a movable bed frame, a horizontally projecting cutter arm rigid with the bed frame, a cutter chain supported on and guided by the cutter arm, a sprocket wheel engaging the cutter chain to drive it, a vertical drive shaft connected to the sprocket wheel in axial alinement therewith, a motor connected with the drive shaft, a rotatable winding drum mounted concentrically with the drive shaft, mechanism for transmitting the power of the motor to rotate the drum, and a feed rope engaging the drum and adapted to extend to a fixed point external to the machine to cause bodily movement of the machine as the drum is rotated.

8. In a mining machine, the combination of a movable bed frame, a horizontally projecting cutter arm rigid with the bed frame, a cutter chain supported on and guided by the cutter arm, a sprocket wheel engaging the cutter chain to drive it, a vertical drive shaft connected to the sprocket wheel in axial alinement therewith, a motor connected with the drive shaft, a rotatable winding drum mounted concentrically with the drive shaft with the periphery at the inner side of the machine exposed along lines parallel to the direction of feed, mechanism for trans-

mitting the power of the motor to rotate the drum in a direction opposite to the direction of rotation of the sprocket wheel, and a feed rope engaging the drum and adapted to extend from the drum at the inner side thereof directly to a fixed point external to the machine.

9. In a mining machine, the combination of a movable bed frame, a horizontally projecting cutter arm rigid with the bed frame, a cutter chain supported on and guided by the cutter arm, a sprocket wheel engaging the cutter chain to drive it, a vertical drive shaft connected to the sprocket wheel in axial alinement therewith, a motor connected with the drive shaft, a rotatable sleeve within which the drive shaft is journaled, mechanism for transmitting the power of the motor to rotate the sleeve at a speed different from that of the shaft, a rotatable winding drum mounted concentrically with the shaft and the sleeve, a manually controllable clutch between the sleeve and the drum, and a feed rope engaging the drum and adapted to extend to a fixed point external to the machine to cause bodily movement of the machine as the drum is rotated.

10. In a mining machine, the combination of a movable bed frame, a horizontally projecting cutter arm rigid with the bed frame, a cutter chain supported on and guided by the cutter arm, a sprocket wheel engaging the cutter chain to drive it, a vertical drive shaft connected to the sprocket wheel in axial alinement therewith, a motor connected with the drive shaft, means comprising a draft rope acting on the inner part of the bed frame to advance the machine laterally along the face of the coal, a rotatable drum mounted concentrically with the drive shaft, a brake for resisting the rotation of the drum, and a rope engaging the drum and adapted to extend rearward from the outer end of the machine to a fixed abutment.

11. In a mining machine, the combination of a movable bed frame, a horizontally projecting cutter arm rigid with the bed frame, a cutter chain supported on and guided by the cutter arm, a sprocket wheel engaging the cutter chain to drive it, a vertical drive shaft connected to the sprocket wheel in axial alinement therewith, a motor connected with the drive shaft, means comprising a draft rope acting on the inner part of the bed frame to advance the machine along the face of the coal, a rotatable drum mounted concentrically with the drive shaft, a releasable brake for resisting the rotation of the drum, mechanism comprising a clutch for transmitting the power of the motor to rotate the drum, and a rope engaging the drum and adapted to extend rearward from the outer end of the machine to a fixed abutment, whereby movement of the machine can be resisted when the brake is applied and

whereby the machine can be moved when the clutch is engaged.

12. In a mining machine, the combination of a movable bed frame, a horizontally projecting cutter arm rigid with the bed frame, a cutter chain supported on and guided by the cutter arm, a sprocket wheel engaging the cutter chain to drive it, a motor connected with the sprocket wheel, two drums mounted on the frame for rotation about the same axis, mechanism for transmitting the power of the motor to rotate one drum, a feed rope engaging the drum and adapted to extend to a fixed point external to the machine to cause bodily movement of the machine as the drum is rotated, a brake for resisting the rotation of the other drum, and a retarding rope engaging the said other drum and adapted to extend to a fixed point external to the machine, whereby the movement of the machine can be resisted.

13. In a mining machine, the combination of a movable bed frame, a horizontally projecting cutter arm rigid with the bed frame, a cutter chain supported and guided by the cutter arm, a sprocket wheel engaging the cutter chain to drive it, a motor connected with the sprocket wheel, two drums mounted on the frame for rotation about the same axis, mechanism comprising manually controllable clutches for transmitting the power of the motor to rotate either of the drums, a feed rope engaging one drum and adapted to extend to a fixed point external to the machine, whereby the machine can be bodily moved as the said drum is rotated, a releasable brake for resisting the rotation of the other drum, and a rope engaging the said other drum and adapted to extend to a fixed point external to the machine, whereby the machine can be moved when the drum is rotated and whereby movement of the machine can be resisted when the brake is applied.

14. In a mining machine, the combination of a movable bed frame, a horizontally projecting cutter arm rigid with the bed frame, a cutter chain supported on and guided by the cutter arm, a sprocket wheel by means of which the cutter chain is driven, a vertical drive shaft connected to the sprocket wheel in axial alinement therewith, a motor connected with the drive shaft, two rotatable drums mounted concentrically with the drive shaft, mechanism for transmitting the power of the motor to rotate one drum, a feed rope engaging the drum and adapted to extend to a fixed point external to the machine to cause bodily movement of the machine as the drum is rotated, a brake for resisting the rotation of the other drum, and a retarding rope engaging the said other drum and adapted to extend to a fixed point external to the machine, whereby movement of the machine can be resisted.

15. In a mining machine, the combination of a movable bed frame, a horizontally projecting cutter arm rigid with the bed frame, a cutter chain supported on and guided by the cutter arm, a sprocket wheel by means of which the cutter chain is driven, a vertical drive shaft connected to the sprocket wheel in axial alinement therewith, a motor connected with the drive shaft, two rotatable winding drums mounted concentrically with the drive shaft, mechanism for transmitting the power of the motor to rotate either of the drums, a feed rope engaging one drum and adapted to extend to a fixed point external to the machine whereby the machine can be bodily moved as the said drum is rotated, a releasable brake for resisting the rotation of the other drum, a rope engaging the said other drum and adapted to extend to a fixed point external to the machine, whereby the machine can be moved when the drum is rotated and whereby the movement of the machine can be resisted when the brake is applied. 70
16. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, a rotatable drive element connected with the motor, a rotatable drum mounted for rotation about the axis of the drive element, a hand-wheel adjacent the drum and having threaded engagement with the drive element, a clutch for connecting the drum with the drive element, the clutch being controlled by the movement of the hand wheel with respect to the drive element, and a rope engaging the drum and adapted to extend to a fixed point to cause bodily movement of the machine as the drum is rotated. 75
17. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, two rotatable drums mounted for rotation about the same axis, the drums being of different diameters, mechanism for transmitting the power of the motor to rotate either the smaller drum at a definite angular speed or the larger drum at the same angular speed, a brake for resisting the rotation of the larger drum, a feed rope engaging the smaller drum and adapted to extend to a fixed point external to the machine to cause bodily movement of the machine as the drum is rotated, and a rope engaging the larger drum and adapted to extend to a point external to the machine, whereby the machine can be moved when the drum is rotated and whereby movement of the machine can be resisted when the brake is applied. 80
18. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, a rotatable drive element connected with the motor, a rotatable drum mounted for rotation about the axis of the drive element, a hand-wheel adjacent the drum and having threaded engagement with the drive element, a clutch for connecting the drum with the drive element, the clutch being controlled by the movement of the hand wheel with respect to the drive element, and a rope engaging the drum and adapted to extend to a fixed point to cause bodily movement of the machine as the drum is rotated. 85
19. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, a rotatable drive element connected with the motor, two rotatable drums mounted for rotation about the axis of the drive element, a hand-wheel between the two drums having threaded engagement with the drive element, two clutches connected with the hand wheel to be controlled by its rotation with respect to the drive element, one clutch serving to connect one drum with the drive element and the other serving to connect the other drum with the drive element, a feed rope engaging one drum and adapted to extend to a fixed point external to the machine to cause bodily movement of the machine as the drum is rotated, a releasable brake for resisting the rotation of the other drum, a rope engaging the said other drum and adapted to extend to a point external to the machine whereby the machine can be moved when the drum is rotated and whereby movement of the machine can be resisted when the brake is applied. 90
20. In a mining machine, the combination of a movable bed frame, a horizontally projecting cutter arm rigid with the bed frame, a cutter chain supported on and guided by the cutter arm, a sprocket wheel by means of which the cutter chain is driven, a clutch element on the sprocket wheel, a motor, a vertical drive shaft connected with the mo- 95

tor and mounted in axial alinement with the sprocket wheel, a clutch element on the shaft, a manually operable device for moving the shaft vertically to bring the clutch element thereon into or out of engagement with the clutch element on the sprocket wheel, a rotatable drum mounted concentrically with the drive shaft and fixed against movement vertically, mechanism for transmitting the power of the motor to rotate the drum, and a feed rope engaging the drum and adapted to extend to a fixed point external to the machine to cause bodily movement of the machine as the drum is rotated.

21. In a mining machine, the combination of a movable bed frame, a horizontally projecting cutter arm rigid with the bed frame, a cutter chain supported on and guided by the cutter arm, a sprocket wheel by means of which the cutter chain is driven, a clutch element on the sprocket wheel, a motor, a vertical drive shaft connected with the motor and mounted in axial alinement with the sprocket wheel, a clutch element on the shaft, a manually operable device for moving the shaft vertically to bring the clutch element into or out of engagement with the clutch element on the sprocket wheel, two rotatable drums mounted concentrically with the drive shaft and fixed against movement vertically, mechanism for transmitting the power of the motor to rotate one drum, a feed rope engaging the drum and adapted to extend to a fixed point external to the machine to cause bodily movement of the machine as the drum is rotated, a brake for resisting the rotation of the other drum, and a retarding rope engaging the said other drum and adapted to extend to a fixed point external to the machine, whereby movement of the machine can be resisted.

22. In a mining machine, the combination of a movable bed frame, a horizontal cutting apparatus projecting from the inner end of the bed frame, propelling mechanism comprising a winding drum and a feed rope having one end fixedly attached to said winding drum and adapted to be extended either toward the right or toward the left to exert a propelling draft in either of said directions on the inner part of the bed frame, a motor for driving the cutting apparatus and the said winding drum, and means for guiding the outer end of the machine comprising a winding drum, a rope having one end fixedly attached to said drum means for retarding the last said drum while under the tension from the rope affixed thereto, and a plurality of guide sheaves on the bed frame arranged so that the last named rope can be carried off from its winding drum either toward the left or toward the right to a fixed abutment.

23. In a mining machine, the combina-

tion of a movable bed frame, a horizontally projecting cutter arm rigid with the bed frame, a cutter chain supported on and guided by the cutter arm, a sprocket wheel by means of which the cutter chain is driven, a vertical drive shaft having its axis in the central longitudinal plane of the machine and connected at its lower end with the sprocket wheel, a motor connected with the shaft, two rotatable drums mounted concentrically with the shaft, means for transmitting the power of the motor to one drum to drive it in either direction in accordance with the direction of rotation of the motor, a feed rope connected with the drum to be wound thereon in either direction according to the desired direction of machine movement, the end of the rope being adapted to extend to a fixed point on either side of the machine whereby the machine can be bodily moved toward the right or left as the drum is rotated, a brake for resisting the rotation of the other drum in either direction, and a retarding rope connected with the said other drum to be wound thereon in either direction according to the desired direction of machine movement, the end of the rope being adapted to extend to a fixed point on either side of the machine whereby movement of the machine toward the right or left can be resisted.

24. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, a rotatable drum mounted on the frame, mechanism for transmitting the power of the motor to rotate the drum, a rope connected at one end with the drum to be wound thereon, a pulley adapted to be engaged by the rope between its ends and to be secured in place at a point external to the machine, and means for securing the other end of the rope to the bed frame at any one of a plurality of elevations.

25. In a mining machine, the combination of a movable bed frame, a horizontally projecting cutter arm rigid with the bed frame, a cutter chain supported on and guided by the cutter arm, a sprocket wheel by means of which the cutter chain is driven, a motor connected with the sprocket wheel, a rotatable drum mounted on the frame, mechanism for transmitting the power of the motor to rotate the drum in either direction according to the direction of rotation of the motor, a feed rope connected at one end with the drum to be wound thereon in either direction according to the desired direction of the machine movement, a pulley adapted to be engaged by the rope between its ends and to be secured in place at a point external to the

machine and on either side thereof according to the desired direction of machine movement, and means for securing the other end of the rope to the bed frame at either side thereof and at any one of a plurality of elevations.

26. In a mining machine, the combination of a movable bed frame, a horizontally projecting cutter arm rigid with the bed frame and provided with a central longitudinal slot, a cutter chain supported on and guided by the cutter arm, a sprocket wheel for driving the cutter chain, a motor connected with the sprocket wheel, a guide block adapted to slidably engage the slot in the cutter arm, a jack for securing the guide block against movement, a rotatable drum on the bed frame connected to be driven by the motor, a rope connected with the drum 10 to be wound thereon, means for connecting the end of the rope with the jack and block at a point in the central longitudinal plane of the machine, whereby the machine as a whole may be moved longitudinally inward 15 to make a sumping cut.

27. In a mining machine, the combination of a movable bed frame, a horizontally projecting cutter arm rigid with the bed frame and provided with a central longitudinal slot, a cutter chain supported on and guided by the cutter arm, a sprocket wheel for driving the cutter chain, a motor connected with the sprocket wheel, a guide block adapted to slidably engage the slot in the cutter arm, 20 a jack for securing the guide block against movement, a rotatable drum on the bed frame connected to be driven by the motor, a rope connected with the drum to be wound thereon, means for guiding the rope to cause 25 it to extend from the bed frame substantially in the central longitudinal plane of the machine, and means for connecting the end of the rope with the jack and block at a point in the central longitudinal plane of 30 the machine, whereby the machine as a whole may be moved longitudinally inward to make a sumping cut.

28. In a mining apparatus, the combination with a mining machine bed frame, cutting apparatus carried thereby, a motor on the bed frame for driving the cutting apparatus, a vertical drive shaft on the mining machine, a clutch element at the lower end of the drive shaft, and a manually operable 35 device at the upper end of the shaft for moving the shaft and the clutch element vertically with respect to the bed frame, of a wheeled truck upon which the mining machine can be supported, and a clutch element 40 on the truck connected with the wheels thereof, the said clutch element being in position to be engaged by the clutch element on the mining machine when the machine is in place on the truck.

29. In a mining apparatus, the combina-

tion of a mining machine bed frame, a cutter chain, a support for the cutter chain mounted on the bed frame and serving to guide the chain in a horizontal path, a sprocket wheel for driving the cutter chain, 70 a motor connected with the sprocket wheel, a vertical drive shaft upon which the sprocket wheel is journaled, a clutch element on the sprocket wheel, a motor connected with the drive shaft, a clutch element at the 75 lower end of the shaft, a manually operable device for moving the said clutch element vertically with respect to the bed frame, the said clutch element when in its upper position engaging the clutch element on the 80 sprocket wheel, a wheeled truck upon which the mining machine can be supported, and a clutch element on the truck connected with the wheels thereof, the said clutch element being in position to be engaged by the clutch 85 element on the mining machine when the machine is in place on the truck.

30. In a mining apparatus, the combination of a mining machine bed frame, a horizontally projecting cutter arm rigid with the bed frame, a cutter chain supported on and guided by the cutter arm, a sprocket wheel by means of which the cutter chain is driven, a clutch element on the sprocket wheel, a vertically movable shaft on which 90 the sprocket wheel is journaled, a clutch element on the lower end of the shaft adapted to engage the clutch element on the sprocket wheel, a motor connected with the shaft, a device at the upper end of the shaft for 95 moving it vertically to bring the clutch element thereon into or out of engagement with the clutch element on the sprocket wheel, a wheeled truck upon which the mining machine can be supported, and a clutch element 100 on the truck connected with the wheels thereof, the said clutch element being in position to be engaged by the said clutch element on the shaft when the mining machine is in place on the truck.

31. In a mining apparatus, the combination of a mining machine frame, a horizontally projecting cutter arm rigid with the bed frame, a cutter chain supported on and guided by the cutter arm, a sprocket wheel 115 by means of which the cutter chain is driven, a motor connected with the sprocket wheel, a drum connected with the motor through a manually controlled friction clutch, a rope connected with said drum and adapted to 120 be wound thereon, its other end being attached to a fixed point toward which the machine will be drawn when the drum is rotated to wind the rope, a second drum connected with the motor through a manually controlled power transmitting friction clutch, a rope connected to the second drum and adapted to be wound thereon, its other end being connected to a fixed point toward 125 which the machine will be drawn when the 130

- second drum is rotated to wind its rope, and a friction brake adapted to resist the unwinding of the second rope from the second mentioned drum, all as and for the purposes 5 set forth.
32. In a mining machine, the combination of a bed frame, a cutter chain, a support for the cutter chain mounted on the bed frame and serving to guide the chain in a horizontal path, a clutch element on the sprocket wheel, a vertical drive shaft in axial alignment with the sprocket wheel and extending upward to the top of the machine, a motor connected to the shaft, a clutch element on 10 the lower end of the shaft, and a device for moving the shaft axially to bring the clutch element thereon into or out of engagement with the clutch element on the sprocket wheel.
33. In a mining machine, the combination of a bed frame, a cutter chain, a support for the cutter chain mounted on the bed frame and serving to guide the chain in a horizontal path, a sprocket wheel for driving the cutter chain, a clutch element on the sprocket wheel, a vertical drive shaft in axial alignment with the sprocket wheel and extending upward to the top of the machine, a motor connected with the shaft, a clutch element on 15 the lower end of the shaft, a device for moving the shaft axially to bring the clutch element thereon into or out of engagement with the clutch element on the sprocket wheel, a rotatable drum mounted concentrically with the drive shaft and fixed against relative axial movement, mechanism for transmitting the power of the motor to rotate the drum, and a rope engaging the drum and adapted to have its end secured at a 20 fixed point to cause the bodily movement of the cutter chain and support as the drum is rotated.
34. In a mining machine, the combination of a bed frame, a cutter chain, a support for the cutter chain mounted on the bed frame and serving to guide the chain in a horizontal path, a sprocket wheel for driving the cutter chain, a vertical drive shaft in alignment therewith, a disengageable clutch between the drive shaft and the sprocket wheel, a motor connected with the drive shaft, a rotatable drum mounted concentrically with the drive shaft, mechanism for transmitting the power of the motor to 25 rotate the drum, and a rope engaging the drum and adapted to have its end secured at a fixed point to cause the bodily movement of the cutter chain and support as the drum is rotated.
35. In a mining machine, the combination of a movable bed frame, cutting apparatus projecting from the inner end of the bed frame, a winding drum rotatably mounted on the bed frame, a draft rope having one end 30 connected to said drum and adapted to ex-
- tend along the face of the coal to exert a forward draft on the inner part of the bed frame, means for adjusting the line of draft of said rope on the machine upward and downward, a motor on the bed frame for 70 driving the cutting apparatus and the winding drum, and means for applying a retarding force to the outer part of the bed frame.
36. In a mining machine, the combination of a movable bed frame, a cutter bar having 75 a longitudinal slot rigid with the bed frame and projecting from the inner end thereof, a cutter chain supported on and guided by the cutter bar, an apertured guide block slidably mounted in the slot of the cutter bar, 80 a jack adapted to pass through the aperture of the guide block and engage the floor of the mine and roof at points in the longitudinal vertical plane of the cutting apparatus, a draft rope, rotary mechanism on the 85 bed frame coöperating with the draft rope to create a tension therein, said rope being adapted to be carried inward from the bed frame to a fixed abutment so that its tension will tend to advance the machine longitudinally, and a motor on the bed frame for 90 driving the cutter chain and the said rotary mechanism.
37. In a mining machine, the combination of a movable bed frame, a cutter bar rigid 95 with the bed frame and projecting from the inner end thereof, a sumping guide device adapted to slidably engage the cutter bar and be fixed in position while the cutter bar and bed frame advance longitudinally into 100 the coal, and means for applying a force to the machine in the central longitudinal plane thereof to force it as an entirety longitudinally toward the face of the coal.
38. In a mining machine, the combination of a movable bed frame, a horizontally projecting cutter arm rigid with the bed frame, a cutter chain supported on and guided by the cutter arm, a sprocket wheel engaging the cutter chain to drive it, means for advancing the machine laterally along the face of the coal comprising a winding drum and a draft rope fixedly fastened thereto and adapted to extend along the face of the coal and exert a forward draft on the inner end 105 of the bed frame, means adapted to retard the outer end of the bed frame comprising a frictionally controlled winding drum and a rope fixedly fastened thereto and adapted to extend rearward from the outer end of 110 the machine to a fixed abutment, a motor, driving connections adapted to cause the power of the motor to actuate the cutter chain and the said winding drums, and means for rendering inoperative the driving 115 connections between the motor and the cutter chain and between the motor and the feeding drum, whereby the retarding drum and rope can be driven independently of the cutter chain and of the feeding drum to 120 125 130

move the machine bodily over the mine floor when the cutter chain is idle.

39. In a mining machine, the combination of a bed frame, cutting apparatus projecting from the inner end of the bed frame, a winding drum mounted on the bed frame, a feed cable having one end secured to said winding drum and adapted to exert a forward draft on the inner part of the bed frame to 5 propel the machine along the face of the coal, a second winding drum mounted on the bed frame, a retarding cable having one of its ends attached to the last named winding drum and being adapted and arranged to 10 extend rearward from the machine to an anchor or the like and exert a retarding draft on the outer part of the bed frame, a motor on the bed frame, driving connections between the motor and the cutting apparatus, driving connections comprising a disengageable clutch between the motor and the first named winding drum, and driving connections between the motor and the retarding cable drum rotating in a direction to 15 wind up the retarding cable, said devices comprising adjustable yieldable friction parts adapted when tightened to cause rotation of the drum in the direction to wind up the retarding cable and when loosened to 20 permit rotation of the drum in the opposite direction with various degrees of frictional resistance.

40. In a mining machine, the combination of a bed frame, cutting apparatus projecting from the inner end of the bed frame, a power actuated cable arranged to exert a forward draft on the inner part of the bed frame to propel the machine along the face of the coal, a retarding cable arranged to 25 exert a rearward draft on the outer part of the bed frame, a winding drum on the bed frame to which one end of the retarding cable is attached, disconnectible power actuated driving devices for the said drum rotating in a direction to wind up the retarding cable, and friction devices adapted to 30 resist the rotation of the drum in the opposite direction when the said driving devices are not in effective operation.

41. In a mining machine, the combination

of a bed frame, cutting apparatus projecting from the inner end of the bed frame, a winding drum mounted on the bed frame, a feed cable having one end connected to the winding drum and arranged to exert a forward draft on the inner part of the bed frame to propel the machine along the face of the coal, a second winding drum mounted on the bed frame, a retarding cable having one end secured to the winding drum and being adapted to extend rearward from the machine to an anchor or the like and exert a retarding draft on the outer part of the bed frame, a motor on the bed frame, gearing between the motor and the first named winding drum adapted to drive said drum at a relatively slow speed, and gearing between the motor and the retarding cable drum adapted to drive the latter at a relatively fast speed, the last named gearing comprising a manually operable friction clutch by which the rotation of the retarding drum can be controlled at will.

42. In a mining machine, the combination of a bed frame, a horizontal cutting apparatus projecting from the inner end of the bed frame, propelling mechanism comprising a winding drum and a feed rope connected to said drum and arranged to extend forward to exert a propelling draft on the inner part of the bed frame, guiding means for the machine comprising a frictionally controlled winding drum and a rope connected to said drum and arranged to extend rearward to exert a retarding draft on the outer part of the bed frame, a motor on the bed frame, driving connections between the motor and cutting apparatus, and two trains of gearing adapted to transmit power of the motor to the winding drums, respectively, and comprising two manually controlled coaxially arranged friction clutches, one adapted to transmit power to the propelling drum and the other to the guiding drum.

In testimony whereof I affix my signature, in presence of two witnesses.

NILS DAVID LEVIN.
